Primary Examiner — Cynthia Ramirez*Assistant Examiner* — Xavier Marti-Santos(74) *Attorney, Agent, or Firm* — Banner & Witcoff, Ltd.(57) **CLAIM**

The ornamental design for a seat with table, as shown and described.

DESCRIPTION

FIG. 1 is a front, right side, top perspective view of a seat with table showing my new design;

FIG. 2 is a left side, top perspective view thereof;

FIG. 3 is a left side, bottom perspective view thereof;

FIG. 4 is a bottom view thereof;

FIG. 5 is a top view thereof;

FIG. 6 is a front perspective view thereof; and,

FIG. 7 is a rear perspective view thereof.

The broken lines in the figures are for the purpose of illustrating portions of the seat with table, which form no part of the claimed design.
